OVEN DOOR CONSTRUCTION

Herbert M. Reeves, Kankakee, Ill., assignor to
 Florence Stove Company, Gardner, Mass., a
 corporation of Massachusetts

Application April 12, 1948, Serial No. 20,435

9 Claims. (Cl. 126—200)

1

The invention relates to doors for cookstoves or ranges and more particularly to doors for closing the oven compartments of such stoves.

One object of the invention is to provide a door of the above general character adapted to be constructed from simple, inexpensive sheet metal stampings and while light in weight, is very strong and rigid.

Another object is to provide an oven door having front and rear panels of enameled sheet metal assembled and secured together in a novel manner affording maximum protection to the enamel coating of the panels in the manufacture of the door and when the door is in use.

Another object is to provide an oven door having a double glazed window opening constructed and arranged in a novel manner which permits the opening to be made of relatively small size so as to minimize heat losses without decreasing the effective range of vision through the window.

Still another object is to provide an insulated type oven door having a double glazed window and embodying novel means for strengthening the door and for supporting the glass panes therein.

Other objects and advantages of the invention will become apparent from the following detailed description of the preferred embodiment illustrated in the accompanying drawings, in which:

Figure 1 is a fragmentary perspective view of a cookstove equipped with an oven door embodying the features of the invention, the door being shown in closed position.

Fig. 2 is a view similar to Fig. 1, showing the door in open position.

Fig. 3 is a rear view of the door with parts broken away to show details of the internal structure.

Fig. 4 is a sectional view taken in a vertical plane substantially on the line 4—4 of Fig. 3.

Fig. 5 is a fragmentary sectional view taken in a horizontal plane substantially on the line 5—5 of Fig. 3.

Fig. 6 is an exploded view of the door liner and the reinforcing structure associated therewith.

Fig. 7 is a fragmentary perspective view showing the manner in which the front window pane is supported on and secured to the door structure.

Fig. 8 is a rear view of the reinforcing member forming a part of the door.

While the invention is susceptible of various modifications and alternative constructions, I have shown in the drawings and will herein de-

2

scribe in detail the preferred embodiment, but it is to be understood that I do not thereby intend to limit the invention to the specific form disclosed, but intend to cover all modifications and alternative constructions falling within the spirit and scope of the invention as expressed in the appended claims.

For purposes of illustration, the invention has been shown as embodied in a door 10 associated with the oven 11 of a cabinet type cookstove 12. In stoves of this type the doors are made of substantial thickness for the accommodation of a layer of insulating material and are mounted so as to lie substantially flush with the insulated drawer and door panels 13 provided for the broiler and utility compartments of the stove.

The door 10, in its preferred form, comprises an outer or face panel 15 (Figs. 1 and 4) and an inner or liner panel 16 (Figs. 2 and 4) both in the form of sheet metal stampings assembled and secured together in spaced interfitting relation to provide smooth inner and outer surfaces for the door. These surfaces are usually finished with a coating of vitreous enamel to enhance their appearance and to facilitate cleaning. The particular door illustrated is provided with a window 17 through which the contents of the oven may be observed while the door is closed, the window being double glazed and embodying features of construction which reduce heat loss, as will appear presently.

In accordance with the invention, the face and liner panels 15 and 16 are constructed and secured together in a novel manner, which permits the front and rear faces of the door to be finished with an enamel coating completely free of flaws or defects and which effectually protects the enamel coating from damage due to rough closing or slamming of the door. To this end the face panel 15 is formed with a rearwardly turned flange 20 and the liner panel 16 is formed with a forwardly turned flange 21 around their respective marginal edges. The liner panel is dimensioned so that the flange 21 is adapted to fit into the flange 20 of the face panel in telescoping relation with a slight but definite clearance between the flanges at all points, as shown in Figs. 4 and 5.

The panels 15 and 16 are secured together in assembled relation by means of connecting links 22 (Fig. 5) coacting with the flanges of the respective panels and constructed so as to provide a substantial degree of resiliency in the connection between the panels. The links 22 are alike in construction, each having generally parallel

end sections 23 and 24 offset laterally with respect to each other and connected by an integral intermediate section 25. The intermediate section 25 is preferably disposed substantially perpendicular to the end sections 23 and 24 and is of a length such as to permit a resilient yielding of the link upon application of pressure lengthwise thereof.

In the assembled door the end sections 23 of the links are permanently secured, as by spot welding, to the outermost flange of the assembly, in this instance the flange 20 of the face panel 15. Four such links are provided in the present instance, two at each side of the door. The other end sections 24 of the links, which are offset inwardly from the flange 20 so as to extend along the inner face of the flange 21 of the liner panel, are removably secured to the latter flange, as by screws 26. Preferably, the flange 21 is formed with inwardly pressed bosses 27 for seating against the links and providing recesses in the outer face of the flange for the accommodation of the heads of the screws 26. The links 22 may also be formed with inwardly turned flanges 28 adapted to engage the inner face of the liner panel 16 to locate the latter in properly spaced relation to the front panel 15 and thereby facilitate the assembly of the panels.

As the connecting links 22 are secured to the flanges of the panels 15 and 16, the faces of the panels are left free of electrode marks or scars so that they can be finished with a flawless enamel coating. Moreover, the enamel coating of the faces of the panels is protected from shocks resulting from contact of the liner panel with the stove frame in the closing of the door as such shocks are largely absorbed by the resiliency of the links 22 and any unabsorbed forces are transmitted to the flanges 20 and 21 instead of to the face portions of the panels. The danger of cracking or chipping the enamel on the faces of the door is thus materially reduced. These advantages are obtained without sacrifice of sturdiness or durability, and at the same time assembly of the door is greatly facilitated.

In order to make the door 10 substantially rigid and capable of supporting relatively heavy loads without deformation when in open position, reinforcing means is provided between the face and the liner panels 15 and 16. The reinforcing means comprises a stiffening member 30 preferably in the form of a sheet metal stamping rigidly secured to the inner face of one of the panels, in this instance the liner panel 16. As shown in Fig. 8, the member 30 comprises a generally rectangular steel plate 31 having its central portion 32 offset from or spaced forwardly from the plane of the sheet and connected therewith by integral webs 33. Additional stiffness is obtained by the provision of upstanding flanges 34 and 34' respectively along the side and the top and bottom edges of the sheet. As shown in Figs. 4 and 6, the flange 34' at the lower edge of the member is rigidly connected by a reinforcing plate 35 with the offset section 32 of the member to provide a rigid, box-like structure within the door.

The stiffening member 30 is preferably attached to the liner panel at a plurality of points adjacent its marginal edges, as, for example, at the four corners. Such attachment may be effected in any preferred manner, as by spot welding or by screws or bolts 36 as shown by way of example. The space between the non-offset portion of the member and the face panel 15 may be filled with

suitable insulating material 37 to minimize the transmission of heat through the door.

In the better grades of stoves the oven doors are commonly provided with window openings which are usually double glazed to minimize heat loss through the window. When used with such doors the stiffening member 30 is constructed in a novel manner to support and properly space the glass panes with which the window openings in the door are glazed. Moreover, the construction is such that the window opening may be made of minimum size without objectionably decreasing the range of vision therethrough.

For accomplishment of the above results, the offset central portion 32 of the plate 31 is cut out to provide a window opening 40 of substantially the same dimensions as the window 41 in the face panel 15. The latter opening is bordered by a generally rounded inturned flange 41, as shown in Figs. 4 and 5, having its inner edge spaced from the plate section 32 sufficiently to receive a glass pane 42. In the particular door illustrated, the flange 41 is tapered slightly with respect to the plane of the panel 15 and the offset portion 32 of the plate 31 is similarly inclined. The pane 42 is thus disposed at a small angle to the plane of the door and more nearly normal to the line of vision of a person looking into the oven.

To simplify construction of the door and to facilitate its assembly, provision is made for supporting the front pane 42 directly on the stiffening member 30. For this purpose a series of clips 43, four in this instance, are spot welded or otherwise secured at one end to the front face of the plate section 32 in positions to coact with the four corners of the front pane. These clips may comprise rectangular strips of sheet metal having a central opening 44 stamped therein for accommodating the corners of the pane. The clips are applied to the door while in a flat condition, as shown in Fig. 6, and after installation of the glass pane, are bent back upon the front surface thereof, as shown in Fig. 7.

The stiffening member 30 and liner panel 16 are constructed and arranged to cooperate in supporting an inner glass pane 45 and in guiding the pane for edgewise movement for installing it in and removing it from the door. To this end the liner panel 16 is formed with a window opening somewhat larger than the rear opening in the stiffening member 30 and such opening is bordered by a raised rib 46 having inturned flanges 47 framing the opening. At the sides of the opening the flanges 47 are extended inwardly to abut against the adjacent face of the plate 31 and are spaced apart substantially the width of the pane 45 to engage the side edges thereof and confine the pane against lateral movement. The flanges 47 at the top and bottom of the opening have their free edge portions 48 (Fig. 4) bent into a plane substantially parallel to the plane of the liner panel and spaced from the plate 31 to provide clearance for the pane 45. Support for the pane is provided by lugs 49 struck out from the plate 31 and projecting under the flange 47 at the bottom of the window opening.

With the above construction, the marginal edge portions of the pane 45 engage along its side and bottom edges with the plate 31 and the pane is normally held in engagement therewith by the flanges 47 at the top and bottom edges of the window opening in the liner panel 16. Downward movement of the pane is limited by the lugs 49, but the clearance provided at the upper edge of

the window opening by the rib 46 permits the pane to be shifted edgewise in a direction upwardly of the door to free its lower edge from the flange 47. When the lower edge is thus freed, the pane may be tilted clear of the liner panel and withdrawn from the door.

To provide a range of vision sufficient to permit proper visual inspection of the oven and at the same time keep the window opening within minimum dimensions, the openings in the face and liner panels 15 and 16 are relatively proportioned and arranged in a novel and advantageous manner. More particularly, the window opening in the face panel 15 is made substantially smaller than the corresponding opening in the liner panel 16 and the lower edge of the latter opening is offset downwardly with respect to the first-mentioned opening, as shown in Fig. 4. Additionally, the side edges of the inner window opening are offset outwardly from the corresponding edges of the front window opening, as shown in Fig. 5.

In view of the downwardly and laterally offset relation of the inner window opening with respect to the outer opening, the webs 33 joining the plate 31 with its offset section 32 are sharply inclined downwardly and laterally to define an expanding range of vision when looking into the oven. In other words, by relatively proportioning and arranging the window openings in the panels 15 and 16 in the manner set forth, it is possible to minimize the dimensions of the outer window opening and at the same time increase the effective range of vision through the window notwithstanding the fact that the door is made of substantial thickness to minimize loss of heat.

The invention also contemplates the attachment of the hinge structure to the door in a novel manner which provides greater strength and rigidity and which relieves the enameled portions of the door of strains. While the door may be provided with hinges of any preferred type, those shown by way of illustration are generally similar in construction to the hinges disclosed and claimed in my copending application Serial No. 650,768, filed February 28, 1946, now abandoned. This hinge comprises a pair of members 50 and 51 pivotally secured together and adapted for attachment respectively to the door and the stove frame. It will be understood, of course, that the door is provided with two hinges, one at each side.

In the particular hinge shown, the member 50 which is attached to the door comprises an elongated sheet metal strip having one end portion of approximately the same width as the flange 34 on the stiffening plate 31 and adapted to be secured thereto as by spot welding. The other end of the strip is offset rearwardly so as to project through the inner face of the door and to extend in the form of an arm substantially beyond the lower edge of the door, as shown in Fig. 6. The liner panel 16 is provided with suitable slots 52 for the accommodation of the projecting ends of the hinge members.

When installed in the stove, the member 51 is suitably secured to the stove frame as by a stud 53, thus providing a fixed base upon which the hinge member 50 may pivot. As the side flanges of the stiffening plate 31 and the members 50 of the hinges are disposed in face-to-face relation through a substantial portion of the length of the members, a strong and rigid connection is insured. Moreover, strains incident to the opening and closing of the door are not transferred to the outer face of the door structure, thereby avoid-

ing any possibility of cracking or chipping the enamel coating thereon.

It will be apparent from the foregoing that the invention provides an oven door of novel and advantageous construction. The door is adapted to be fabricated from simple, inexpensive sheet metal stamping, thus producing a structure which is light in weight yet strong and rigid. By reason of the novel manner in which the parts of the door are arranged and interconnected, marring of the front or rear faces of the door is avoided, thus enabling the faces to be finished with flawless enamel coatings. Moreover, the enamel coating is effectually protected from damage when subjected to rough treatment.

The improved door also provides a window construction which affords maximum range of vision, while maintaining the dimensions of the window opening at a minimum so that heat losses are substantially reduced. Moreover, the window opening is completely framed in a manner such that it presents a neat and attractive appearance.

I claim as my invention:

1. An oven door comprising, in combination, a face section including a generally rectangular sheet metal panel having rearwardly turned flanges along its marginal edges, a liner section comprising a sheet metal panel having forwardly turned flanges along its marginal edges adapted to fit within the flanges of said face section, and sheet metal connecting links coating with the flanges of said two sections to secure the sections together, said links being permanently secured to the flanges of said face section and the flanges of said liner section being removably secured to said links.

2. An oven door comprising, in combination, a face section including a generally rectangular sheet metal panel having rearwardly turned flanges along its marginal edges, a liner section comprising a sheet metal panel having forwardly turned flanges along its marginal edges adapted to fit within the flanges of said face section, and sheet metal connecting links secured at opposite ends to the flanges of said two sections to connect the sections in assembled relation, the end portions of said links being offset with respect to each other to provide a substantial degree of resiliency in the connection between the sections.

3. An oven door comprising, in combination, a pair of sheet metal panels secured together in spaced parallel relation, a stiffening member comprising a metal plate substantially smaller than said panels and having its marginal edges rigidly secured to the inner face of one of the panels, upturned flanges on the side edges of said plate, and hinge members for said door rigidly secured to said flanges and projecting through the panel forming the inner face of the door.

4. An oven door comprising, in combination, a pair of sheet metal panels secured together in spaced parallel relation, said panels having aligned window openings, a stiffening member comprising a metal plate substantially smaller than said panels and having its marginal edges rigidly secured to one of the panels, said plate having its central portion offset from the plane of the plate so as to lie closely adjacent the other of said panels and having an opening substantially aligned with the window opening in said other panel, a glass pane for closing said last-mentioned window opening and means on said plate for securing said pane to the plate independently of said other panel to facilitate assembly of the door structure.

5. An oven door comprising, in combination, a pair of sheet metal panels secured together in spaced parallel relation, said panels having aligned window openings, glass panes for closing said window openings, a stiffening member comprising a metal plate substantially smaller than said panels and having its marginal edges rigidly secured to one of the panels, said plate having its central portion offset from the plane of the plate so as to lie closely adjacent the other of said panels and having an opening substantially aligned with the window opening in said other panel, means for securing one of the glass panes to said plate independently of the adjacent one of said panels in a position effective to close the window opening in the panel, and lugs struck out from said plate for supporting the other glass pane in spaced relation to said one pane, the offset portion of said plate being operative to determine the spacing of said glass panes.

6. An oven door comprising, in combination, a face section comprising a sheet metal panel having a rectangular window opening in its upper central portion, a liner section secured to said face section and comprising a second sheet metal panel having a rectangular window opening with its side and bottom edges offset laterally and downwardly with respect to the corresponding side and bottom edges of the opening in said first panel, a stiffening member comprising a metal plate secured at its marginal edges to the inner face of one of said panels, said plate having its central portion offset from the plane of the plate and joined to the marginal edge portion of the plate by webs inclined at an angle to said plane, said offset portion of the plate having an opening of substantially the same shape and dimensions as the opening in said first panel and aligned therewith, said webs meeting the marginal edge portions of the plate substantially in line with the side and bottom edges of the opening in said second panel, and glass panes interposed between said plate and both said panels to close the openings in the panels.

7. In an oven door, in combination, a generally rectangular sheet metal panel having its outer surface enameled and defining the front face of the door, a rearwardly turned flange formed around the marginal edges of said panel, a second sheet metal panel assembled in spaced parallel relation with said first panel, a forwardly turned flange formed around the marginal edges of said second panel, said second panel being dimensioned to permit the flange thereon to fit into the flange of said first panel in telescoping relation, a plurality of connecting links securing said panels together, each of said links having offset end sections disposed substantially parallel to the flanges of the respective panels and rigidly secured thereto, and an intermediate section connecting said end sections, said intermediate section being disposed substantially parallel to the plane of the door and effective to minimize the shock transmitted to said first panel from said second panel incident to the closing of the door.

8. In an oven door, in combination, a generally rectangular sheet metal panel having its outer surface enameled and defining the front face of the door, a rearwardly turned flange formed around the marginal edges of said panel, a second panel assembled with said first panel to define

the rear face of the door, a forwardly turned flange formed around the marginal edges of said second panel, said panels being dimensioned to permit the flange of one of the panels to fit into the flange of the other panel in telescoping relation, a plurality of connecting links cooperating with the flanges of said panels to secure the panels together, each of said links having end sections disposed in spaced parallel planes and connected by an intermediate section substantially perpendicular to the end sections, one end section of each link being secured to the outer one of the flanges and the other end section being secured to the inner flange, and inwardly pressed bosses in said inner flange providing seats for the end sections of the links secured to that flange.

9. An oven door comprising, in combination, a face section comprising a sheet metal panel having a rectangular window opening in its upper central portion, a liner section secured to said face section and comprising a second sheet metal panel having a rectangular window opening with its side and bottom edges offset laterally and downwardly with respect to the corresponding side and bottom edges of the opening in said first panel, a stiffening member comprising a metal plate secured at its marginal edges to the inner face of one of said panels, said plate having its central portion offset from the plane of the plate and joined to the marginal edge portion of the plate by webs inclined at an angle to said plane, said offset portion of the plate having an opening of substantially the same shape and dimensions as the opening in said first panel and aligned therewith, said webs meeting the marginal edge portions of the plate substantially in line with the side and bottom edges of the opening in said second panel, glass panes for closing the openings in said panels, means for securing one of said panes to said plate independently of the adjacent panel, and means on said plate and the other panel cooperating to removably retain the other pane in assembled relation with the door.
